UNITED STATES PATENT OFFICE.

CHARLES C. ARMSTRONG, OF HUNTINGTON, WEST VIRGINIA.

FASTENING DEVICE FOR HINGED BOX MEMBERS.

1,344,846.

Specification of Letters Patent. Patented June 29, 1920.

Application filed October 1, 1919. Serial No. 327,701.

To all whom it may concern:

Be it known that I, CHARLES C. ARMSTRONG, a citizen of the United States, and resident of Huntington, West Virginia, 5 have invented certain new and useful Improvements in Fastening Devices for Hinged Box Members, of which the following is a specification.

My present invention relates to combined 10 fastening devices and locks designed more especially for boxes of the type comprising two tray like members hinged together with an intermediate hinged flap such as disclosed in Letters Patent of the United States 15 granted to me July 4, 1916, under No. 1,189,902.

The invention aims to provide a combined 20 lock and latch which may be readily struck up from sheet metal and which shall be composed of a minimum number of parts thereby greatly reducing the cost of manufacture.

I have also aimed to provide a combined 25 lock and latch in which one of the members of the fastening device shall serve as se- 25 curing means for the handle.

With these and other objects in view the 30 invention includes the novel features of construction and arrangement and combination of parts hereinafter described and defined 30 by the appended claims.

An embodiment of my invention is illustrated in the accompanying drawing in 35 which:

Figure 1 is a plan view of the box.

Fig. 2 is a front elevation.

Fig. 3 is a partial central transverse section.

Fig. 4 is a partial central longitudinal section through the closed box showing the 40 fastening device as it would appear from the inside of the box.

Fig. 5 is a detail plan view and Figs. 6 and 7 are plan views of the two sheet metal members which comprise the fastening de- 45 vice.

In these drawings 1 and 2 comprise the two main members of the box which is shown as representative of any device to which my improved lock or fastening may 50 be applied, each of which is shown in the form of an elongated shallow tray, these two members being hinged together at 3. The member 1 is provided with a turned edge 4 and the member 2 is provided with a flared 55 edge 5 adapted to fit over the turned edge 4, when one member is swung over upon the

other member as shown in Fig. 3. A leaf or flap 8 is provided hinged about the same axis as the hinged members at 3. The flap or leaf 8 is adapted to cover either member 60 1 or 2, of the box.

My improved locking device is shown as applied to the box at the point 12 (Fig. 2) and this, in addition to locking the two main members together, will lock the flap or leaf 65 8 in position by engaging the edge of the opening at 8^a formed in said leaf. The wall of this opening is adapted to engage the end 15^a of the catch 15^b forming a part of the lock, this catch having its edge inclined 70 70 for the edge of the opening to ride against. A finger opening is provided at 8^b by which the user may lift the leaf from the catch, it being necessary for him however to exert slight pressure laterally or in the direction 75 of the arrow α in Fig. 3 to spring the catch out of connection with the edge 8^a of the leaf.

The catch which serves to hold the two box sections together and to retain the partition is formed as an integral part of a single 80 blank, shown in Fig. 6, which also serves as the catch spring, co-operates with the lock and is utilized as means for retaining the handle which is indicated at 18.

To this end this blank is stamped from 85 suitable spring metal, and comprises a cross bar 15 with portions 15^a and 15^b extending transversely from opposite sides thereof.

The extremity 15^a of the portion 15^b is folded over upon itself to form the catch 90 hereinbefore referred to as shown in Fig. 3 and it is provided with an opening d designed to engage a projection 1^a carried by the box section 1. The two end portions of the bar 15 are designed to be secured to the 95 inner face of the front wall of box section 2 by suitable means, such as rivets 6 and the portion 15^b has its end folded back upon itself to form a holder for the movable member of the lock.

This comprises a single sheet metal stamping having its main portion of substantially saucer shape as indicated at 16 surmounted by a struck up circular boss 16^a which is designed to engage a circular opening e in 105 the overturned portion 15^b after said movable member has been inserted therebeneath, said circular boss forming a pivot on which said movable member oscillates.

The central portion of this boss is struck 110 out and inwardly to form a key engaging projection 16^b by which the movable member

may be oscillated in the manner hereinafter described to lock and unlock the box.

The front wall of the box section 2 is provided with an opening in which is inserted 5 a push button 17 which is preferably formed by stamping up a piece of sheet metal into cup shape having its closed outer face provided with a key slot 17^a and having on its inner edge a marginal flange 17^b designed to 10 overlie the inner face of the box section 2 beneath the member 15 by which it is held in position. The member 15 being of spring metal holds the push button normally pressed outwardly in the position shown in 15 Fig. 3, but pressure on the push button forces the central portion of the member 15 inwardly toward the interior of the box, removing the edge of opening *d* from engagement with projection 1^a thus releasing 20 the catch or latch which holds the box sections together.

One of the rivet holes, either in the member 15 or in the box section 2 is elongated to permit the flexing of the member or 25 bar 15.

The member 15 is also provided with an alining key opening *f* and a suitable key may be inserted therethrough and on turning the key its web or bit will engage the 30 projection 16^b and rotate the member 16.

This member is provided with a locking projection 16^c which is designed to engage an undercut recess or slot 1^b in the projection 1^a thereby holding the portion 15^d against 35 inward movement and preventing the disengagement of the catch.

The member 16 is provided with ears or 40 projections 16^d which engage the edges of the base of portion 15^d and serve as stops for limiting the movement of member 16 and the member 15 is provided with struck up bosses 15^e which bear against the faces of projections 16^d and offer frictional resistance to its movement, thus holding it in 45 its locking or unlocking position.

I also utilize the member 15 as a means for securing the handle 18 to the box and to this end provide the ends of the bar with projecting portions 15^f which are bent to 50 semi-circular or hooked form and inserted through slots in the front wall of the box. The straight alined end projections of the handle are then placed in these hook shaped recesses whereafter the bar 15 is placed or 55 swung flat against the inner wall of the box section, holding the handle securely in position. The projection 1^a may be made in the form of a solid metal stud having a reduced portion passed through an opening in the 60 wall of box section 1 and upset to hold it in place as clearly shown in Fig. 3.

In the operation of my improved fastening means, when the locking projection is 65 out of engagement with the slot 1^b and it is desired to open the box, an inward push

upon the push button 17 will cause the tongue part 15^b to move inward until the opening *d* ceases to engage the projection 1^a, when the sections of the box may be swung apart. As the upper section Fig. 1 is 70 opened or swung upwardly, the partition 8 will be carried with it by engagement of the portion 15^a with the leaf or partition. After the said upper section has been swung 75 back to a horizontal position and it is desired to have access to the interior thereof the leaf or partition may be swung away from section 1 by pressing catch portion 15^a toward the front of the box (or to the left from the position shown in Fig. 1) which 80 will bring its free or holding ends into alignment with the cut away portion of the leaf or partition which may then be swung away from section 1 by inserting the finger in the opening 8^b.

When this box is closed and it is desired to lock it against being opened except by the use of a key, such key is inserted in the alining key openings or slots 17^a and *f* until its web or bit is in line with the projection 16^b of the member 16. The turning of the key will then rotate the member 16 until its projection 16^c engages the under cut portion or slot 1^b in the projection 1^a which under cut portion lies to the rear of the portion 15^a of the spring tongue. In this position, the part 15^d is locked against inward movement, or in other words, cannot be pushed in by pressure on the push piece or button and consequently the sections are 95 locked together.

Having thus described my invention what I claim is:

1. A lock or fastening device for box members comprising a bar of resilient material having end portions secured to the box wall and having a projection overlying the other box section provided with an opening, a projection on the inner wall of said other box section engaging said opening, 105 and a push button seated in an opening in the first box section and operatively engaging said resilient member.

2. A lock or fastening device for box members comprising a bar of resilient material having its ends secured to the inner wall of one box section, said bar having an integral projection or tongue overlying the other box section and provided with an opening, a keeper projection on said other 110 box cover having an undercut recess, a push button carried by the first named box section and operatively engaging said resilient member, said push button having a key opening, and a key operated rotary member 115 carried by said resilient member having a projection designed to engage the recess in said keeper projection.

3. A lock or fastening device for box members comprising a bar of resilient ma- 130

terial having its ends secured to the wall of one section, a keeper on the other box section having a locking recess, a tongue projecting from one side of said bar having a 5 part to engage said keeper and a part disposed parallel to and overlying the central part of said bar and provided with a recess, a rotary member between the said overlying part and said bar having a boss rotatably

10 seated in said recess, said rotary member having a keeper engaging projection, a push button in the wall of the first box section operatively engaging said bar, said push button and said bar having alining key openings, and said rotary member, a key bit engaging part.

4. A lock or fastening device for box members comprising a bar of resilient material having its ends secured to the wall 20 of one section, a keeper on the other box section having a locking recess, a tongue projecting from one side of said bar having a part to engage said keeper and a part disposed parallel to and overlying the central 25 part of said bar and provided with a recess, a rotary member between the said overlying part and said bar having a boss rotatably seated in said recess, said rotary member having a keeper engaging projection, a push button seated in an opening in the wall of the first box section and having a marginal flange lying between said bar and said wall, said push button and said bar having alining key receiving openings 30 and said rotary member, a key bit engaging part.

5. A lock or fastening device for box members comprising a bar of resilient material having its ends secured to the wall 40 of one section, a keeper on the other box section having a locking recess, a tongue projecting from one side of said bar having a part to engage said keeper and a part disposed parallel to and overlying the 45 central part of said bar and provided with a recess, a rotary member between the said overlying part and said bar having a boss rotatably seated in said recess, said rotary

member having a keeper engaging projection, a push button seated in an opening in 50 the wall of the first box section and having a marginal flange lying between said bar and said wall, said push button and said bar having alining key receiving openings and said rotary member, a key bit engaging 55 part, said rotary member having integral opposed stop projections.

6. In a fastening device for a box comprising two hinged sections and an intermediate hinged leaf provided with a recessed edge, a bar of resilient material having its ends secured to the wall of one box section, a keeper projection carried by the other box section, said bar having a part projected through the recess in the leaf when 65 the box is closed and provided with an opening to receive the keeper projection, the portion of said part beyond the opening being inclined backwardly and then doubled back on itself to form a leaf engaging catch, 70 and means for springing said bar to disengage the keeper projection and opening.

7. In a fastening device for a box comprising two hinged sections and an intermediate hinged leaf, provided with a recessed edge, a bar of resilient material having its ends secured to the wall of one of the sections, a keeper carried by the other box section, said bar having a transverse extension on one side provided with a recess to 75 engage said keeper and having a doubled back end to form a leaf engaging catch, said bar having a second projection provided with a part overlying the central portion of the bar provided with a recess, a rotary member lying between the overturned part and bar and having a part rotatably engaging said recess, a push button carried by the first box section and engaging said rotary member, said push button and said bar having a key opening and said rotary member, a key bit engaging part, said rotary member having a keeper engaging projection.

In testimony whereof, I affix my signature.
CHARLES C. ARMSTRONG.
